WRENCH

John E. Torbert, Jr., National City, Calif.

Application July 16, 1935, Serial No. 31,673

1 Claim. (Cl. 145—62)

This invention relates to an improved wrench and seeks, among other objects, to provide a device of this character which may be converted instantly from a T-handle type to a speed or crank type wrench.

Another object of the invention is to provide a wrench having a handle which may be shifted for converting the wrench from the T-type to the speed type, which handle will remain in a 10 desired set position after setting.

A further object of the invention is to provide a wrench having a shank adapted to receive bits and tools of various kinds.

And a still further object of the invention is 15 to provide a device of this character which will be characterized by the utmost simplicity and which will be capable of manufacture at a nominal figure to retail at an attractive price.

Other and incidental objects of the invention 20 will render themselves apparent as the description of the invention proceeds.

My improved wrench is illustrated in the accompanying drawing, wherein:

Figure 1 is a longitudinal sectional view of the 25 device as it would appear set as a speed wrench, and showing, in dotted lines, the handle set for use as a T-type wrench.

Figure 2 is a fragmentary sectional view on the line 2—2 of Figure 1, looking in the direction indicated by the arrows.

Figure 3 is an enlarged fragmentary detail plan view showing a slightly modified construction.

Referring now more particularly to the accompanying drawing, wherein like numerals of reference indicate like parts, my improved wrench includes a shank 1 which is formed at its lower end with a square portion 2. The square portion is formed with an opening 3 in which is carried a ball latch 4. The latch 4 is normally urged 40 outwardly in the opening by a spring 5. The shank 1 is bent at substantially right angles at its upper end portion, as shown at 6, and is again bent straight, as shown at 7, and is flattened to provide a handle mounting block 8. The block 45 8 is formed with an arcuate end wall 9 terminating at each end in shoulders 10 and 11. Formed in the end wall 9 are sockets 12.

Swingingly connected with the handle mounting block 8 is a yoke 13 which straddles the block and is provided with an upwardly projecting cylindrical mounting shank 14 having an axial bore 15 therein. Carried in the axial bore is a plunger 16 which is adapted to selectively engage the sockets 12 and is normally urged into said sockets 55 by means of a coil spring 17. Connecting the

block 8 with the yoke 13 is a bearing screw 18 which is hollow axially and is provided with spanner slots 19 to receive a suitable spanner wrench when dismounting the yoke from the block.

Rotatably mounted on the cylindrical mounting shank 14 is a handle comprising an inner bearing sleeve 20 which extends throughout substantially three-fourths the length of the handle and is connected to a relatively thick base 21 10 which also provides an end connection for the outer manually engageable handle portion 22. Connecting the sleeve 20 with the cylindrical shank 14 is a washer 23 which is clamped in position by means of a screw 24. The sleeve 20, 15 together with the entire handle structure, is free to rotate about the cylindrical shank 14. Closing the outer end of the handle is a cap 25. As best seen in Figure 1 of the drawing, the base 21 is relatively thick and is reduced in diameter 20 and is provided with an end wall or shoulder 26 which abuts the end face of the yoke 13 and cooperates with the washer 23 and screw 24 for limiting longitudinal shifting movement of the handle on the cylindrical shank.

The curved wall 9 of the block 8 is disposed between the arms of the yoke with a portion thereof in constant sliding engagement with the inner face of the bight portion 27 of said yoke. When the handle is in upward position, to 30 form a speed wrench, as shown in full lines in Figure 1, the shoulder 10 will abut the outer end of the bight portion 27 and the outer face of the block 8 will lie flush with the corresponding outer edges of the arms of the yoke so that a smooth 35 surface will be provided. The plunger 16 will retain the handle in its upward position while the device is being used as a speed wrench.

When it is desired to use the device as a T-type wrench, it is only necessary to swing the handle 40 downwardly so that the plunger 16 will ride out of the uppermost socket 12 and into the lowermost of said sockets. When the handle is in its lowermost position, the shoulder 11 will abut the opposite end of the bight portion 27 of the yoke and will limit further downward swinging movement. As best seen in dotted lines in Figure 1, the handle, in downward position, is disposed in substantially parallel relation to the portion 6 of 50 the shank 1 and the handle is of such a length that the plane of the shank 1 will intersect the handle 22 at substantially right angles thereto medially of the length of said handle. It will be seen that the device, when used as a T-type 55

wrench, will be effectually balanced and thus very easy to operate.

Attention is particularly directed to the fact that the device may be used as a T-type wrench to start the work, as for example a bolt, and, after the bolt has been well started in its opening, the handle may be quickly snapped to the speed position and the wrench rotated as a speed wrench at a high rate of speed. It should be further understood that the handle, when in upward position, or speed wrench position, will be disposed angularly with respect to the shank so that it may be comfortably held in the hand during operation thereof.

Referring now to the modification of the invention, as shown in Figure 3 of the drawing, the numeral 30 indicates a straight shank which is adapted, at its lower end, to receive a bit in the usual manner. The shank carries a ratchet wheel 31 at its upper end and said ratchet wheel is straddled by a yoke 32 which includes arms 33. The lateral portion 34 is formed integral with the yoke and is bent to form a vertical portion, as shown at 35, and terminates in a mounting block 36 which is identical in construction with the mounting block 8. A handle 37 cooperates with the mounting block 36, as in the preferred embodiment of the invention. Carried between the arms 33 of the yoke and engageable with the ratchet wheel 31 is a pawl 38. A suitable pawl is carried at the opposite side of the yoke to engage the ratchet wheel diametrically of the pawl 38 and both of said pawls are retractable for permitting reverse rotation of the ratchet wheel and shank with respect to the yoke. Both of the pawls may be engaged with the ratchet wheel

simultaneously and when this is done, the device will operate entirely as in the preferred embodiment of the invention. However, when the wrench is to be used in close quarters, and it is possible to turn the handle but a fraction of its 5 rotative travel, one or the other of the pawls may be disengaged for permitting ratchet and pawl action of the shank with respect to the handle. As stated, the objects of the invention and the operation just described are substantially identical with the preferred form.

It is thought that the construction and operation of the invention will be understood from the foregoing.

Having thus described the invention, what I claim is:

In a wrench, a shank having a flattened rear end portion providing a mounting block, a yoke straddling the mounting block and having a rearwardly extending mounting shank circular in 20 cross section, a pin extending through the yoke and the mounting block to pivotally connect the yoke with the mounting block, a hollow cylindrical handle open at its rear end and having a solid forward portion and an inner tubular bearing sleeve extending rearwardly therefrom and fitting snugly about the mounting shank to rotatably mount the handle thereon, the forward end of said handle defining a flat annular shoulder abutting said yoke, a screw threaded into the 30 rear end of said mounting shank, a washer fitting about said screw and engaging the rear ends of the mounting shank and the sleeve to hold the sleeve upon the mounting shank, and a detachable cap for closing the rear end of said handle. 35
